UNITED STATES PATENT OFFICE.

JOHN C. MCCLURE, OF LAWTON, OKLAHOMA.

CRUDE-OIL BURNER.

1,158,523.

Specification of Letters Patent.

Patented Nov. 2, 1915.

Application filed March 22, 1915. Serial No. 16,159.

To all whom it may concern:

Be it known that I, JOHN C. MCCLURE, a citizen of the United States, residing at Lawton, in the county of Comanche and State of Oklahoma, have invented certain new and useful Improvements in Crude-Oil Burners; and I do declare the following to be a full, clear, and exact description of the invention, such as will enable others skilled in the art to which it appertains to make and use the same.

My invention relates broadly to improvements in heating apparatus, and specifically to an improved type of crude oil burner therefor.

The object of the invention is to provide a device of this class so constructed as to allow even the poorest grades of crude oil to be burned to advantage and with little waste, this end being attained by the provision of certain novel features of construction and combination hereinafter described and more particularly pointed out in the claims.

In describing the invention, I shall refer to the accompanying drawing wherein like references designate corresponding parts throughout the various views and wherein:

Figure 1 is a side elevation of crude oil burner constructed in accordance with my invention; Fig. 2 is a vertical section thereof; and, Fig. 3 is a horizontal section as seen along the plane indicated by the line 2-3 of Fig. 1.

In this drawing constituting a part of the application, the numeral 1 designates an upright supporting element which may be in the form of an oil supply tube as shown in the drawings, or may well be an upright rod or the like, provided other means were used for supplying oil to the upper end thereof. In the present application, the lower end of the element 1 is shown as equipped with any preferred type of stop 2, this stop being herein shown in the form of a T-coupling into which an oil supply pipe 3 is tapped, this pipe being led to any preferred form of fuel tank 4. It will be evident that two of the nipples of the T-coupling are occupied by the element 1 and pipe 3, and by reference to Figs. 1 and 2, it will be seen that a cut-off valve 5 is tapped into the lowermost nipple thereof, this valve being used for a purpose to be hereinafter described.

Having a central opening 6 loosely receiv-

ing the element 1, is the bottom 7 of a refuse pan 8 in which ashes or the like 9 are disposed. The bottom 7 rests directly upon the stop 2 whereby it is held against downward movement, this being essential since other parts of the burner are supported by the pan, for which purpose said bottom is shown as provided with an upright spacer 10 in the form of a sleeve formed integrally therewith and loosely surrounding the element 1. Resting upon this spacer 10, is the lowermost and largest oil and flame spreading plate 11 of a trio of such plates, this plate 11 as well as the intermediate plate 12 being in the form of flat disks, while the uppermost plate 13 is conical. All the plates 11, 12 and 13 are provided with central openings closely receiving the element 1, the plate 12 is spaced from the plate 11 by a spacing sleeve 14 loosely surrounding said element 1, and the uppermost and smallest plate 13 is spaced from the intermediate plate 12 by a third spacing sleeve 15 which likewise loosely surrounds the element 1. It is to be observed that the upper end of the aforesaid supporting element 1 is free from projections, thus allowing any one of the oil and flame spreading plates and the spacing sleeves to be quickly and easily removed. It will likewise be observed that the entire refuse pan 8 may be so removed if desired. These features are very important, since devices of this class burning crude oil often need cleaning on account of the accumulations of impurities upon the various parts thereof. It will be evident that by constructing the device in the manner above described, all parts thereof may be disassembled for this purpose, thus allowing the best results to be obtained at all times.

In applying the burner to use, it is disposed in a suitable shell or casing, or in some cases may be left in the open, since no amount of fresh air will hinder the burning thereof. The valve 3^a in the fuel delivering pipe 3 is then opened, thus allowing the crude oil to be discharged from the top of the element 1 upon the uppermost spreading plate 13. From this plate 13 the oil runs downwardly upon the intermediate and lower plates 12 and 11 respectively, and then drips into the ashes or the like in the pan 8. These ashes, or any other preferred absorbent material will of course be impregnated with the crude oil, whereupon they serve as a wick. The oil at this point may

now be ignited, whereupon the numerous spreading plates will become heated, thereby causing the crude oil dripping thereon to be more readily vaporized and more easily burnt. Particular emphasis is laid upon the fact that the oil is prevented from vaporizing until it is disposed upon some of the spreader plates, this result being accomplished by so disposing said plates as to prevent the flame from hugging the element 1 which as above stated is in the present case a feed pipe.

When the burner is to be extinguished the valve 3^a is again closed thereby cutting off the supply of fuel, after which the valve 5 is preferably opened to allow the oil remaining in the element 1 and lower end of the pipe 3 to be drained therefrom into any preferred receptacle (not shown). By so doing the numerous materials composing crude oil are prevented from gumming in the pipes, thus preventing them from clogging.

From the foregoing description, taken in connection with the accompanying drawings, it will be evident to those skilled in the art to which the invention relates that although very simple and inexpensive construction has been provided for reducing the invention to an operative device, the latter will be extremely efficient in operation and will burn crude oil to as great advantage as higher grades of oil have heretofore been consumed.

Particular emphasis is laid upon the construction for allowing the entire burner to be disassembled, since by this means all parts thereof may be easily cleaned when necessary, thus insuring that the best results be obtained.

I claim:

1. A crude oil burner comprising a refuse pan, an upright supporting element rising therefrom, a removable fuel and flame spreader spaced above the pan and having an opening closely receiving the aforesaid supporting element, and a spacing sleeve

loosely surrounding the latter and disposed between the pan and the spreader.

2. A crude oil burner comprising a refuse 50 pan, an upright supporting element rising therefrom, a plurality of vertically spaced oil and flame spreading plates disposed above the refuse pan and having openings receiving the aforesaid supporting element, 55 a spacing sleeve surrounding the lower end of the supporting element and disposed between the lowermost spreading plate and the refuse pan, and additional spacing sleeves surrounding the upper and intermediate 60 portions of the supporting element and interposed between the remaining spreading plates thereon.

3. A crude oil burner comprising a stop member in the form of a T-coupling, an 65 upright supporting element rising therefrom, a drain valve depending from said coupling, a refuse pan having a central opening to receive the supporting element and adapted to rest on the stop member, said 70 pan also having an upright spacing sleeve surrounding said opening and formed integral with its bottom, a plurality of spaced oil and flame spreading plates disposed above the refuse pan and having openings 75 closely receiving the aforesaid supporting element, the lowermost of said plates being supported on the upper end of said spacing sleeve, a cone-shaped oil and flame spreader disposed adjacent the top of said supporting element, additional spacing sleeves surrounding the upper and intermediate portions of the supporting element and interposed between the spreading plates and the cone-shaped spreader, and a valved supply 80 pipe threaded into said T-coupling.

In testimony whereof I have hereunto set my hand in presence of two subscribing witnesses.

JOHN C. McCLURE.
